UNITED STATES PATENT OFFICE.

JACOB S. ALLEN, OF PHILADELPHIA, PENNSYLVANIA, ASSIGNOR TO ELEANOR C. ALLEN, OF PHILADELPHIA, PENNSYLVANIA.

DERRICK.

1,033,652.

Specification of Letters Patent. Patented July 23, 1912.

Application filed May 8, 1911. Serial No. 625,772.

To all whom it may concern:

Be it known that I, JACOB S. ALLEN, a citizen of the United States, residing in Philadelphia, Pennsylvania, have invented 5 certain Improvements in Derricks, of which the following is a specification.

My invention relates to certain improvements in derricks of the type having a mast journaled in bearings at the top and at the 10 bottom, with a movable boom pivoted at the base of the mast.

One object of my invention is to improve the construction of a derrick of this type; to reduce the wear of the parts, and to prevent 15 breaking of the lower pivot.

A further object of my invention is to construct the outer end of the boom so that it will be of greater strength than heretofore, and will provide means for properly 20 guiding the rope which passes around the outer boom sheave.

In the accompanying drawings:—Figure 1, is a side view of my improved derrick; Fig. 2, is a side view, partly in section, of 25 the foot of the derrick; Fig. 3, is an enlarged side view of the head of the mast, showing the upper bearings; Fig. 4, is a side view of the outer end of the boom; Fig. 5, is a plan view of the foot block step; Fig. 6, 30 is a detached plan view of the foot block; Fig. 7, is an inverted plan view of the same; Fig. 8, is a sectional view of the foot block on the line 8—8, Fig. 6; Fig. 9, is a detached view of the mast head gudgeon pin; Fig. 10, 35 is an end view of the boom; Fig. 11, is a sectional view on the line 11—11, Fig. 4, and Fig. 12, is a sectional plan on the line 12—12, Fig. 2.

Referring to Fig. 1 of the drawings, in 40 the present instance, A is a base having sills *a* of any form desired, and mounted on the sills is the step casting B forming a bearing for the foot block C to which the mast D is secured. On the upper end of the 45 mast is a gudgeon pin E, which passes through eyes in plates *f*, secured to the struts F, forming the frame of the derrick. The boom G is pivotally mounted on the foot block C.

50 The foot block step B is made, as clearly shown in Figs. 2, 5 and 12, and has a central opening *b*, in which rests the gudgeon or pivot head *c*, which depends from the foot block C. Projecting upward from the center of

the opening is a tapered flange *b'*, which 55 surrounds the central opening *b* for the passage of the ropes leading to and from the sheaves H. These sheaves are mounted on a pin *h* carried by brackets *h'* depending from the step B. In the annular space surrounding the flange *b* of the step B is a bearing ring *k*, and the head *c'* of the gudgeon *c* rests directly upon this ring. Plates *b*, *b* are secured to the step and extend over the flanged head fitting around the neck of 60 the gudgeon *c*, as illustrated in Fig. 2. These plates allow the gudgeon to move freely on its bearing ring, yet prevent it from being withdrawn from the step. Straps *b* extend across the joints of the 70 plates, as shown in Fig. 12, and the securing bolts pass through both the straps and plates, making a very substantial construction.

The foot block has a central opening *c*, in 75 line with the opening *b*, for the passage of the ropes. The underside of the head *c* of the gudgeon *c* is curved, as clearly shown in Fig. 8; the curve running parallel with a line at right angles to the pivot of the boom. 80 The foot block rests upon the ring *k* at each side of the center, as illustrated at *x*, Fig. 8, and at *x*, *x*, Fig. 7, and as the foot block rocks when the boom is carrying a load, it will roll on the ring, the bearing being 85 always at each side of the center line; thus distributing the load on each side of the center, instead of concentrating the load at the forward end of the gudgeon, as heretofore. 90

When the load was concentrated at a single point at the forward end of the gudgeon, the pressure was so great as to cause the head of the gudgeon to crack, breaking pieces from the head and making 95 the bearing imperfect. I find that by making the head in the form of a rocker, the load is carried by the gudgeon at each side of the center, leaving the forward end practically free from the dead weight of the 100 boom and its load.

Instead of making a pocket in the foot block, as heretofore, I form a bracket *c* at the rear of the foot block and strengthen it by side flanges *c*. The mast is bolted 105 to the vertical web *c* of the foot block by bolts *d*. By this construction, the lodgment of water at the base of the boom is

prevented and the mast is securely held to the foot block by said bolts.

The mast head gudgeon is preferably made in a single piece and from a forging or steel casting. It has a body portion, as at E, and a projecting pin e, which passes through the eyes in the plates f. There is an annular recess at the upper end, in which is mounted a split ring f'. The body portion E has flanges e' at each side, through which the securing bolts d' are passed; said bolts firmly holding the gudgeon to the upper end of the mast.

The boom G is slotted at its lower end to receive the sheave I, which is mounted on the pivot pin i, adapted to bearings formed in the cheek pieces i', projecting from the foot block C. This pivot pin i also forms the pivot for the boom G. A sheave N is mounted on a transverse pivot pin n in a slot near the upper end of the boom. This pivot pin passes through plates n' inserted in the side of the boom, as illustrated in Fig. 11.

In order to strengthen the end of the boom and to provide means for suspending the block forming part of the tackle, and also to form guides for the rope passing around the sheave N, I provide four angle bars M, M'; arranging two bars M on the upper surface of the boom and two bars M' on the lower surface thereof. The bars of both sets are spaced apart, as clearly shown in Fig. 11, and, as they extend from the end of the boom past the sheave end, they act as guides for the rope passing around said sheave. The bars project beyond the end of the boom as clearly illustrated in Fig. 4, and connecting the two sets of angle bars at the end is a solid bar P, which extends from one pair of angle bars to the other and is secured thereto by bolts m, m'. The angle bars are secured to the boom by through bolts m' so that the bars of the upper set are coupled to those of the lower set by bolts and the ends of the bars are coupled by the solid bar P.

Hung from the lower bolt m' is the pulley block S having a sheave s, thus the block is at the extreme end of the boom and the downward pull of this block is not only taken by the lower angle bars M', but is also taken by the upper angle bars through the solid end bar P.

Suspended from the block S is the block T, having a sheave t, around which passes the rope n'. This rope is secured to the block T and also passes around the sheave s and the sheave N to the sheave I, through the openings c' and b', and around one of the sheaves H to the rope drum.

Secured to the upper bolt m is the block V, having two sheaves v, v', and mounted on a pin w, passing through the opening e' in the body of the gudgeon E, is a block W,

having sheaves w', w''. The rope y passes around these several sheaves and through openings c' and b', around one of the sheaves H to a power controlled drum. The position of the boom is controlled by the power mechanism to which the rope y is attached.

It will be seen by the above construction that I provide a derrick which will lift a comparatively heavy load and in which there is no liability of the lower gudgeon being broken as it is allowed to rock in its step; the weight being distributed on each side of the longitudinal center of the foot block; the outer end of the boom being also materially strengthened provides a means from which a block can be suspended.

I claim:

1. The combination in a derrick, of a foot block step having a recess therein, a foot block having a gudgeon extending into the recess, a mast secured to the foot block, a boom pivoted to the foot block, the lower end of the gudgeon being curved to form a rocker, the curve lying in the plane of oscillation of the boom.

2. The combination in a derrick having a mast and boom, of a step, said step having a recess, a ring mounted within the recess, a foot block having a gudgeon extending into the recess, a head on the gudgeon, the lower end of the head being curved to form a rocker, the curve lying in the plane of oscillation of the boom so that said head will rest at each side upon the ring, a mast secured to the foot block, and a boom pivotally mounted on the foot block, the parts being so arranged that when a load is suspended from the boom the head of the gudgeon will rock on the ring.

3. The combination in a derrick, of a base frame, a foot block step mounted thereon, sheaves carried by the foot block step, said foot block step having a central opening through which the ropes pass from the sheaves and having a recess surrounding the opening and a flange projecting from the base of the recess, a loose ring mounted between the flange and the wall of the recess, a foot block having an opening in line with the opening in the step, a gudgeon on the foot block extending into the recess, a head on the gudgeon resting on the ring within the recess, plates secured to the step extending over the head of the gudgeon, the end of the head being curved so as to form a rocker, a mast secured to the foot block, and a boom pivotally mounted on the foot block.

4. The combination in a derrick, of a foot block, a mast, a boom pivoted to the foot block and having a vertical recess near its outer end, a sheave mounted in the recess, angle bars arranged longitudinally on each side of the recess and on the upper and

lower surfaces of the boom and forming guides for the rope passing around the sheave and reinforcing the end of the boom.

5. The combination in a derrick, of a boom, two sets of longitudinally arranged angle bars, one set located on the upper side of the boom and the other set located on the lower side of the boom, said angle bars being spaced apart, a bar extending across 10 the end of the boom, and bolts connecting the bar to the angle bars.

6. The combination in a derrick, of a boom, two sets of angle bars, one set being arranged longitudinally on the upper side 15 of the boom and the other set being arranged longitudinally on the under side of the boom, said boom being recessed, a sheave mounted in the recess and extending between the bars of each set, the bars forming 20 guides for the ropes passing around the boom, a bar extending across the end of the

boom, bolts connecting the said bar with the angle bars, one of the bolts acting as a pivot for the block around which the hoisting rope of the boom passes, the other bolt 25 forming the pivot for the hoisting block of the load.

7. The combination in a derrick, of a foot block step having a recess therein, a foot block having a gudgeon extending into 30 the recess, a mast secured to the foot block, two plates secured to the step and fitting around the gudgeon, straps extending over the joints of said plates, and bolts securing both the straps and plates to the step. 35

In testimony whereof, I have signed my name to this specification, in the presence of two subscribing witnesses.

JACOB S. ALLEN.
